(57) **ABSTRACT**

A connector includes a resin member which includes a protruding portion extending in a right and left direction when viewed in an up and down direction, a frame portion having an annular shape surrounding the protruding portion when viewed in the up and down direction, and a coupling portion between the protruding portion and the frame portion when viewed in the up and down direction and coupling the protruding portion to the frame portion. A plurality of signal terminals is supported by the frame portion and arranged in the right and left direction in a region in front of or in back of the protruding portion. The floating terminal covers at least part of a left end of the protruding portion when viewed in the up and down direction and is not connected to any of terminals of a connector, including the signal terminals and a ground terminal.

CONNECTOR INCLUDING A RESIN BODY MEMBER, SIGNAL TERMINALS AND A GROUND TERMINAL

CROSS-REFERENCE TO RELATED APPLICATION

This application claims benefit of priority to Japanese Patent Application No. 2022-012630, filed Jan. 31, 2022, the entire content of which is incorporated herein by reference.

BACKGROUND

Technical Field

The present disclosure relates to a connector.

Background Art

For example, a receptacle connector described in Japanese Unexamined Patent Application Publication No. 2006-331679 is known as an disclosure related to an existing connector. The receptacle connector includes a receptacle housing, a plurality of receptacle contacts, and a receptacle member. The receptacle housing is a resin member. The receptacle housing includes a receptacle fitting portion and a receptacle outer wall portion. The receptacle fitting portion extends in a right and left direction. When viewed in an up and down direction, the receptacle outer wall portion surrounds the receptacle fitting portion. Each of the plurality of receptacle contacts is a signal terminal. The plurality of receptacle contacts is supported by the receptacle housing. The receptacle member is a ground terminal. The receptacle member includes a first supported portion supported by the left end of the receptacle fitting portion and a second supported portion supported by the left end of the receptacle outer wall portion. The first supported portion and the second supported portion are coupled to each other.

Incidentally, it is desired that the receptacle connector described in Japanese Unexamined Patent Application Publication No. 2006-331679 be used in a high frequency band.

SUMMARY

The present disclosure provides a connector that can be used in a high frequency band.

A connector according to an aspect of the present disclosure includes a resin body member, a plurality of signal terminals supported by the resin body member, a ground terminal supported by the resin body member, and a floating terminal supported by the resin body member. The resin body member includes a protruding portion extending in a right and left direction when viewed in an up and down direction, a frame portion having an annular shape surrounding the protruding portion when viewed in the up and down direction, and a coupling portion located between the protruding portion and the frame portion when viewed in the up and down direction, the coupling portion coupling the protruding portion to the frame portion. The plurality of signal terminals is supported by the frame portion so as to be arranged in the right and left direction in a region in front of or in back of the protruding portion. The floating terminal covers at least part of a left end of the protruding portion when viewed in the up and down direction and is not connected to any of terminals of the connector, including the plurality of signal terminals and the ground terminal. The ground terminal is supported by the frame portion so as to

be opposed to the floating terminal in a front and rear direction or in the right and left direction.

Hereinafter, a positional relationship among members in the specification will be defined. A first member to a third member are components of a connector set. In the specification, the first member and the second member arranged in a front and rear direction represent the following state. This is a state where, when the first member and the second member are viewed in a direction perpendicular to the front and rear direction, both the first member and the second member are disposed on a selected straight line representing the front and rear direction. In the specification, the first member and the second member arranged in the front and rear direction when viewed in an up and down direction represent the following state. When the first member and the second member are viewed in the up and down direction, both the first member and the second member are disposed on a selected straight line representing the front and rear direction. In this case, when the first member and the second member are viewed in a right and left direction different from the up and down direction, any one of the first member and the second member does not need to be disposed on a selected straight line representing the front and rear direction. The first member and the second member may be in contact with each other. The first member and the second member may be separated from each other. The third member may be present between the first member and the second member. This definition also applies to directions other than the front and rear direction.

In the specification, a state where the first member is disposed on or over the second member means the following state. At least part of the first member is located just on or over the second member. Therefore, when viewed in the up and down direction, the first member overlaps the second member. This definition also applies to directions other than the up and down direction.

In the specification, a state where the first member is disposed on or above the second member includes a case where at least part of the first member is located just on or over the second member and a case where the first member is not located just on or over the second member and the first member is located obliquely above the second member. In this case, when viewed in the up and down direction, the first member does not need to overlap the second member. The term "obliquely above" includes, for example, upper left and upper right. This definition also applies to directions other than the up and down direction.

In the specification, unless otherwise specified, parts of the first member are defined as follows. A front part of the first member means a front half of the first member. A rear part of the first member means a rear half of the first member. A left part of the first member means a left half of the first member. A right part of the first member means a right half of the first member. An upper part of the first member means an upper half of the first member. A lower part of the first member means a lower half of the first member. A front end of the first member means a forward end of the first member. A rear end of the first member means a rearward end of the first member. A left end of the first member means a leftward end of the first member. A right end of the first member means a rightward end of the first member. An upper end of the first member means an upward end of the first member. A lower end of the first member means a downward end of the first member. A front end part of the first member means the front end of the first member and its neighborhood. A rear end part of the first member means the rear end of the first member and its neighborhood.

A left end part of the first member means the left end of the first member and its neighborhood. A right end part of the first member means the right end of the first member and its neighborhood. An upper end part of the first member means the upper end of the first member and its neighborhood. A lower end part of the first member means the lower end of the first member and its neighborhood.

When selected two members in the specification are defined as the first member and the second member, the relationship between the selected two members means as follows. In the specification, a state where the first member is supported by the second member includes a case where the first member is attached to (that is, fixed to) the second member so as to be not movable with respect to the second member and a case where the first member is attached to the second member so as to be movable with respect to the second member. A state where the first member is supported by the second member includes both a case where the first member is directly attached to the second member and a case where the first member is attached to the second member via the third member.

In the specification, a state where the first member is held by the second member includes a case where the first member is attached to (that is, fixed to) the second member so as to be not movable with respect to the second member and does not include a case where the first member is attached to the second member so as to be movable with respect to the second member. A state where the first member is held by the second member includes both a case where the first member is directly attached to the second member and a case where the first member is attached to the second member via the third member.

In the specification, the phrase "the first member and the second member are electrically connected" means that the first member and the second member are electrically continuous. Therefore, the first member and the second member may be in contact with each other or the first member and the second member do not need to be in contact with each other. When the first member and the second member are not in contact with each other, the third member having electrical conductivity is disposed between the first member and the second member.

BRIEF DESCRIPTION OF THE DRAWINGS

FIG. 1 is a perspective view of a connector set 1; FIG. 2 is a perspective view of a first connector 10; FIG. 3 is a top view of the first connector 10; FIG. 4 is a perspective view of a floating terminal 15l; FIG. 5 is a perspective view of a ground terminal 14l; FIG. 6 is a perspective view of a ground terminal 16b; FIG. 7 is a perspective view of a second connector 110; and FIG. 8 is a cross-sectional view taken along the line A-A in FIG. 1.

DETAILED DESCRIPTION

Hereinafter, a connector set 1 including a first connector 10 according to an embodiment of the present disclosure will be described. FIG. 1 is a perspective view of the connector set 1.

In the following description, as shown in FIG. 1, a direction in which a second connector 110 and the first connector 10 are arranged is defined as an up and down direction. A direction in which signal terminals 13a to 13v (see FIG. 2) are arranged in the first connector 10 is defined

as a right and left direction. The right and left direction is orthogonal to the up and down direction. A direction orthogonal to the right and left direction and the up and down direction is defined as a front and rear direction. 5 However, the up and down direction, the right and left direction, and the front and rear direction in the specification are directions defined for the sake of convenience of description and do not need to coincide with an up and down direction, a right and left direction, and a front and rear direction during use of the connector set 1.

The connector set 1 is, for example, used to connect two circuit boards. The connector set 1 includes the first connector 10 and the second connector 110. When the first connector 10 and the second connector 110 are connected, 15 the second connector 110 is located on or over the first connector 10.

Structure of First Connector

Next, the structure of the first connector 10 will be described. FIG. 2 is a perspective view of the first connector 20 10. FIG. 3 is a top view of the first connector 10. FIG. 4 is a perspective view of a floating terminal 15l. FIG. 5 is a perspective view of a ground terminal 14l. FIG. 6 is a perspective view of a ground terminal 16b.

As shown in FIGS. 2 and 3, the first connector 10 includes 25 a resin body member 12, signal terminals 13a to 13v, ground terminals 14l, 14r, floating terminals 15l, 15r, and ground terminals 16a to 16d.

As shown in FIG. 2, the resin body member 12 includes 30 a protruding portion 12a, a frame portion 12b, and a coupling portion 12c (see FIG. 3). When viewed in the up and down direction, the protruding portion 12a extends in the right and left direction. More specifically, the protruding portion 12a has a rectangular parallelepiped shape. When viewed in the up and down direction, the protruding portion 35 12a has two long sides extending in the right and left direction and two short sides extending in the front and rear direction.

When viewed in the up and down direction, the frame portion 12b has an annular shape surrounding the protruding 40 portion 12a. More specifically, when viewed in the up and down direction, the frame portion 12b has a rectangular outer edge and a rectangular inner edge. When viewed in the up and down direction, each of the outer edge of the frame portion 12b and the inner edge of the frame portion 12b has 45 two long sides extending in the right and left direction and two short sides extending in the front and rear direction. When viewed in the up and down direction, the protruding portion 12a is located in a region surrounded by the inner edge of the frame portion 12b. The protruding portion 12a is not in contact with the frame portion 12b.

As shown in FIG. 3, when viewed in the up and down direction, the coupling portion 12c is located between the protruding portion 12a and the frame portion 12b and couples the protruding portion 12a to the frame portion 12b. 55 In the present embodiment, the coupling portion 12c couples the lower part of the protruding portion 12a to the lower part of the frame portion 12b. The material of the resin body member 12 is an electrically insulating material. The material of the resin body member 12 is, for example, a resin.

A radio-frequency signal is input to and output from each 60 of the signal terminals 13a to 13v. The signal terminals 13a to 13v are supported by the resin body member 12. More specifically, part of each of the signal terminals 13a to 13k is embedded in the rear side of the frame portion 12b. Thus, 65 the signal terminals 13a to 13k are supported by the frame portion 12b so as to be arranged in the right and left direction in a region in back of the protruding portion 12a. The signal

terminals 13a to 13k are arranged in a line in this order from the left to the right. Part of each of the signal terminals 13l to 13v is embedded in the front side of the frame portion 12b. The signal terminals 13l to 13v are supported by the frame portion 12b so as to be arranged in the right and left direction in a region in front of the protruding portion 12a. The signal terminals 13l to 13v are respectively located in front of the signal terminals 13a to 13k. The signal terminals 13l to 13v are arranged in a line in this order from the left to the right. Each of the signal terminals 13a to 13k is manufactured by bending a rod metal member. The material of the signal terminals 13a to 13k is, for example, a copper-based material, such as phosphor bronze.

The floating terminal 15l is not connected to any of the terminals of the first connector 10, including the signal terminals 13a to 13v and the ground terminals 14l, 14r (details will be described later). Therefore, the potential of the floating terminal 15l is a floating potential. The floating terminal 15l is supported by the resin body member 12. As shown in FIGS. 2 and 3, when viewed in the up and down direction, the floating terminal 15l covers at least part of the left end of the protruding portion 12a. As shown in FIG. 4, the floating terminal 15l includes a first part 15la, a second part 15lb, a third part 15lc, and a floating protrusion 15ld. The first part 15la is located on the top surface and the left surface of the protruding portion 12a. More accurately, the first part 15la covers part of the left end of the top surface of the protruding portion 12a and part of the left surface of the protruding portion 12a. The second part 15lb is located on the front surface of the protruding portion 12a. More accurately, the second part 15lb extends in the forward direction from the first part 15la. The second part 15lb covers part of the left end of the front surface of the protruding portion 12a. The third part 15lc is located on the rear surface of the protruding portion 12a. More accurately, the third part 15lc extends in the rearward direction from the first part 15la. The third part 15lc covers part of the left end of the rear surface of the protruding portion 12a.

Here, the first part 15la and the second part 15lb are coupled on the top surface of the protruding portion 12a. Therefore, the first part 15la and the second part 15lb are not coupled on the left surface or the front surface of the protruding portion 12a. The first part 15la and the third part 15lc are coupled on the top surface of the protruding portion 12a. Therefore, the first part 15la and the third part 15lc are not coupled on the left surface or the rear surface of the protruding portion 12a. In addition, the width of the first part 15la in the front and rear direction is greater than any of the width of the second part 15lb in the right and left direction and the width of the third part 15lc in the right and left direction.

The floating protrusion 15ld extends in the leftward direction from the lower end of the first part 15la. The width of the first part 15la in the front and rear direction is greater than the width of the floating protrusion 15ld in the front and rear direction. The floating terminal 15l is manufactured by bending a metal member. The material of the floating terminal 15l is, for example, a copper-based material, such as phosphor bronze. The structure of the floating terminal 15r and the structure of the floating terminal 15l are bilaterally symmetrical, so the description of the structure of the floating terminal 15r is omitted.

The ground terminal 14l is connected to a ground potential. The ground terminal 14l is supported by the resin body member 12. Specifically, the ground terminal 14l is supported by the frame portion 12b so as to be opposed to the floating terminal 15l in the front and rear direction and in the

right and left direction. Hereinafter, the structure of the ground terminal 14l will be described.

As shown in FIG. 5, the ground terminal 14l includes a first part 14la, a second part 14lb, a third part 14lc, connecting parts 14ld, 14le, and a ground protrusion 14lf (see FIGS. 2 and 3). The first part 14la is provided on the left surface, the top surface, and the right surface of the left side of the frame portion 12b. As shown in FIG. 2, part of the first part 14la is embedded in the left side of the frame portion 12b. Thus, the first part 14la is opposed to the floating terminal 15l in the right and left direction. The second part 14lb is provided on the front surface, the top surface, and the rear surface of the left end of the front side of the frame portion 12b. Part of the second part 14lb is embedded in the front side of the frame portion 12b. Thus, the second part 14lb is opposed to the floating terminal 15l in the front and rear direction. The third part 14lc is provided on the front surface, the top surface, and the rear surface of the left end of the rear side of the frame portion 12b. Part of the third part 14lc is embedded in the rear side of the frame portion 12b. Thus, the third part 14lc is opposed to the floating terminal 15l in the front and rear direction.

The connecting part 14ld couples the first part 14la to the second part 14lb. The connecting part 14le couples the first part 14la to the third part 14lc. The ground protrusion 14lf extends in the rightward direction from the lower end of the first part 14la. The ground terminal 14l is manufactured by bending a metal member. The material of the ground terminal 14l is, for example, a copper-based material, such as phosphor bronze. The structure of the ground terminal 14r and the structure of the ground terminal 14l are bilaterally symmetrical, so the description of the structure of the ground terminal 14r is omitted.

The ground terminal 16b is connected to a ground potential. The ground terminal 16b is supported by the resin body member 12. In the present embodiment, the ground terminal 16b is supported by the left front part of the resin body member 12. As shown in FIG. 6, the ground terminal 16b includes a contact part 16ba, a spring part 16bb, a fixing part 16bc, and an external connecting part 16bd. The spring part 16bb, the fixing part 16bc, and the external connecting part 16bd are arranged in this order from the right to the left. The external connecting part 16bd is a part to which solder is applied when the first connector 10 is mounted on the circuit board. The fixing part 16bc is embedded in the resin body member 12.

The spring part 16bb is not supported by the resin body member 12. Therefore, the spring part 16bb is elastically deformable so as to deflect in the front and rear direction. The contact part 16ba extends in the rearward direction from the right end of the spring part 16bb. The ground terminal 16b is manufactured by bending a metal member. The material of the ground terminal 16b is, for example, a copper-based material, such as phosphor bronze. The structure of the ground terminal 16a and the structure of the ground terminal 16b are symmetrical in the front and back, so the description of the structure of the ground terminal 16a is omitted. The structure of the ground terminal 16d and the structure of the ground terminal 16b are bilaterally symmetrical, so the description of the structure of the ground terminal 16d is omitted. The structure of the ground terminal 16c and the structure of the ground terminal 16a are bilaterally symmetrical, so the description of the structure of the ground terminal 16c is omitted.

As shown in FIG. 3, in the first connector 10 as described above, when viewed in the up and down direction, a through-hole H1 extending through the coupling portion 12c

in the up and down direction is provided in at least part of a region between the first part **14la** and the floating terminal **15l**. When viewed in the up and down direction, the ground protrusion **14lf** protrudes into the through-hole **H1**. When viewed in the up and down direction, the floating protrusion **15ld** protrudes into the through-hole **H1**. The ground protrusion **14lf** and the floating protrusion **15ld** are arranged in the right and left direction. The structure of a through-hole **Hr** and the structure of the through-hole **H1** are bilaterally symmetrical, so the description of the structure of the through-hole **Hr** is omitted.

The first connector **10** as described above is mounted on the circuit board. At this time, parts of the signal terminals **13a** to **13v**, ground terminals **14l**, **14r**, floating terminals **15l**, **15r**, and ground terminals **16a** to **16d** are exposed from the bottom surface of the resin body member **12**. Solder is applied to each of these parts. Thus, the signal terminals **13a** to **13v**, the ground terminals **14l**, **14r**, the floating terminals **15l**, **15r**, and the ground terminals **16a** to **16d** are respectively connected to the electrodes of the circuit board.

Structure of Second Connector

Next, the structure of the second connector **110** will be described. FIG. 7 is a perspective view of the second connector **110**. FIG. 7 is a perspective view of the second connector **110**.

As shown in FIG. 7, the second connector **110** includes a resin body member **112**, signal terminals **113a** to **113v**, and ground terminals **114l**, **114r**.

The resin body member **112** includes a bottom portion **112a** and a frame portion **112b**. When viewed in the up and down direction, the frame portion **112b** has an annular shape. More specifically, when viewed in the up and down direction, the frame portion **112b** has a rectangular outer edge and a rectangular inner edge. When viewed in the up and down direction, each of the outer edge of the frame portion **112b** and the inner edge of the frame portion **112b** has two long sides extending in the right and left direction and two short sides extending in the front and rear direction. As shown in FIG. 7, when viewed in the up and down direction, the bottom portion **112a** closes the top surface of a region surrounded by the frame portion **112b**. The material of the resin body member **112** is an electrically insulating material. The material of the resin body member **112** is, for example, a resin.

A radio-frequency signal is input to and output from each of the signal terminals **113a** to **113v**. The signal terminals **113a** to **113v** are supported by the resin body member **112**. More specifically, part of each of the signal terminals **113a** to **113k** is embedded in the rear side of the frame portion **112b**. The signal terminals **113a** to **113k** are arranged in a line in this order from the left to the right. Part of each of the signal terminals **113l** to **113v** is embedded in the front side of the frame portion **112b**. The signal terminals **113l** to **113v** are respectively located in front of the signal terminals **113a** to **113k**. The signal terminals **113l** to **113v** are arranged in a line in this order from the left to the right. Each of the signal terminals **113a** to **113k** is manufactured by bending a rod metal member. The material of the signal terminals **113a** to **113k** is, for example, a copper-based material, such as phosphor bronze.

The ground terminal **114l** is connected to a ground potential. The ground terminal **114l** is supported by the resin body member **112**. Part of the ground terminal **114l** is embedded in the left end of the front side of the frame portion **112b**, the left end of the rear side of the frame portion **112b**, and the left side of the frame portion **112b**. The ground terminal **114l** is manufactured by bending a metal member.

The material of the ground terminal **114l** is, for example, a copper-based material, such as phosphor bronze. The structure of the ground terminal **114r** and the structure of the ground terminal **114l** are bilaterally symmetrical, so the description of the structure of the ground terminal **114r** is omitted.

Structure of Connector Set

Next, the structure of the connector set **1** will be described. FIG. 8 is a cross-sectional view taken along the line A-A in FIG. 1.

As shown in FIGS. 1 and 8, the frame portion **112b** of the second connector **110** is inserted in a region surrounded by the frame portion **12b** of the first connector **10**. At this time, the protruding portion **12a** of the first connector **10** is inserted in a region surrounded by the frame portion **112b** of the second connector **110**. Thus, the signal terminals **13a** to **13v** respectively contact with the signal terminals **113a** to **113v**. The ground terminals **14l**, **14r** respectively contact with the ground terminals **114l**, **114r**. Furthermore, the ground terminals **16a**, **16b** contact with the ground terminal **114l**. The ground terminals **16c**, **16d** contact with the ground terminal **114r**.

However, the floating terminals **15l**, **15r** do not contact with the signal terminals **113a** to **113v** or the ground terminals **114l**, **114r**. Thus, in a state where the second connector **110** is connected to the first connector **10** as well, the potential of each of the floating terminals **15l**, **15r** remains at a floating potential.

Advantageous Effects

With the first connector **10**, the first connector **10** can be used in a high frequency band. More specifically, in the receptacle connector described in Japanese Unexamined Patent Application Publication No. 2006-331679, the receptacle member is a ground terminal. The receptacle member includes a first supported portion supported by the left end of the receptacle fitting portion and a second supported portion supported by the left end of the receptacle outer wall portion. The first supported portion and the second supported portion are coupled to each other. Therefore, the first supported portion corresponds to the floating terminal **15l**. The second supported portion corresponds to the ground terminal **14l**. Therefore, the receptacle connector described in Japanese Unexamined Patent Application Publication No. 2006-331679 has a structure in which the ground terminal **14l** and the floating terminal **15l** of the first connector **10** are coupled. In this case, a capacitance tends to be formed between the first supported portion and each signal terminal. As a result, a resonant frequency that is generated in the receptacle connector decreases. Therefore, it is difficult to use the receptacle connector described in Japanese Unexamined Patent Application Publication No. 2006-331679 in a high frequency band.

For this reason, in the first connector **10**, the floating terminal **15l** is not connected to any of terminals of the first connector **10** including the plurality of signal terminals **13a** to **13v** and the ground terminals **14l**, **14r** when viewed in the up and down direction. Thus, the potential of the floating terminal **15l** is a floating potential. In this case, a capacitance is difficult to be formed between the floating terminal **15l** and each of the signal terminals **13a** to **13v**. As a result, a resonant frequency that is generated in the first connector **10** tends to increase. Thus, with the first connector **10**, the first connector **10** can be used in a high frequency band.

With the first connector **10**, the floating terminal **15l** covers at least part of the left end of the protruding portion **12a** when viewed in the up and down direction. Thus, the left end of the protruding portion **12a** is protected by the

floating terminal **15l**. As a result, when the second connector **110** is connected to the first connector **10**, contact of the ground terminal **114l** with the left end of the protruding portion **12a** is suppressed. As described above, with the first connector **10**, breakage of the protruding portion **12a** is reduced.

With the first connector **10**, the first connector **10** is usable in a high frequency band additionally depending on the following reason. More specifically, when viewed in the up and down direction, the through-hole **H1** extending through the coupling portion **12c** in the up and down direction is provided in at least part of a region between the first part **14la** and the floating terminal **15l**. Thus, air is present in the region between the first part **14la** and the floating terminal **15l**. Therefore, the dielectric constant of the region between the first part **14la** and the floating terminal **15l** decreases. Thus, a capacitance is difficult to be formed between the first part **14la** and the floating terminal **15l**. As a result, a resonant frequency that is generated in the first connector **10** tends to decrease. Thus, with the first connector **10**, the first connector **10** can be used in a high frequency band.

With the first connector **10**, a misalignment is difficult to occur in the positional relationship between the ground terminal **14l** and the floating terminal **15l**. More specifically, the ground terminal **14l** includes the ground protrusion **14lf** protruding into the through-hole **H1** when viewed in the up and down direction. When viewed in the up and down direction, the floating terminal **15l** includes the floating protrusion **15ld** protruding into the through-hole **H1**. The ground protrusion **14lf** and the floating protrusion **15ld** are arranged in the right and left direction. Thus, the first connector **10** is able to be assembled by the following procedure. Initially, the ground terminal **14l** and the floating terminal **15l** are set in a state where the ground protrusion **14lf** and the floating protrusion **15ld** are coupled. Then, the ground terminal **14l** and the floating terminal **15l** are insert-molded to form the resin body member **12**. After that, the ground protrusion **14lf** and the floating protrusion **15ld** are cut at the through-hole **H1**. In this way, the resin body member **12** is formed in a state where the ground terminal **14l** and the floating terminal **15l** are united, with the result that a misalignment is difficult to occur in the positional relationship between the ground terminal **14l** and the floating terminal **15l**.

In the first connector **10**, the width of the first part **15la** in the front and rear direction is greater than the width of the floating protrusion **15ld** in the front and rear direction. In other words, the width of the floating protrusion **15ld** in the front and rear direction is less than the width of the first part **15la** in the front and rear direction. Therefore, a capacitance is difficult to be formed in the floating protrusion **15ld**.

In the first connector **10**, the first part **15la** and the second part **15lb** are not coupled on the left surface or the front surface of the protruding portion **12a**. The first part **15la** and the third part **15lc** are not coupled on the left surface or the rear surface of the protruding portion **12a**. An area in which the floating terminal **15l** and the ground terminal **14l** are opposed to each other reduces. As a result, a capacitance to be formed between the floating terminal **15l** and the ground terminal **14l** reduces.

In the first connector **10**, the first part **15la** provides a function to guide the ground terminal **114l**, so it is desirable that the width of the first part **15la** in the front and rear direction be large. On the other hand, from the viewpoint of reducing a capacitance to be generated in the first connector **10**, it is desirable that the width of the second part **15lb** in the right and left direction and the width of the third part **15lc**

in the right and left direction be small. For this reason, the width of the first part **15la** in the front and rear direction is greater than any of the width of the second part **15lb** in the right and left direction and the width of the third part **15lc** in the right and left direction. Here, the first part **15la** and the second part **15lb** are connected in series, and the first part **15la** and the third part **15lc** are connected in series. In this case, even when a capacitance that is generated in the first part **15la** increases, a capacitance that is generated in the second part **15lb** and a capacitance that is generated in the third part **15lc** are small, so the resultant capacitance is suppressed to a smaller amount. Thus, with the first connector **10**, while the floating terminal **15l** functions to guide the ground terminal **114l**, an increase in capacitance to be generated in the first connector **10** is suppressed.

OTHER EMBODIMENTS

The connector according to the present disclosure is not limited to the first connector **10** and may be changed within the scope of the purport of the present disclosure.

The ground terminals **14r**, **16a** to **16d**, and the floating terminal **15r** are not indispensable components.

In the specification, the annular shape is not limited to a complete ring and includes a partially cut-out ring. However, in the annular shape, the ratio of the cut-out part to the ring is lower than or equal to 20%.

The ground terminal **14l** just needs to be opposed to the floating terminal **15l** in the front and rear direction or in the right and left direction. Therefore, the ground terminal **14l** may be configured so as to be opposed to the floating terminal **15l** in the front and rear direction and not opposed to the floating terminal **15l** in the right and left direction. The ground terminal **14l** may be configured so as to be opposed to the floating terminal **15l** in the right and left direction and not opposed to the floating terminal **15l** in the front and rear direction.

The through-holes **H1**, **Hr** do not need to be provided.

The ground protrusion **14lf** and the floating protrusion **15ld** are not indispensable components.

The floating terminals **15l**, **15r** may be connected to the electrodes of the circuit board or may be configured not to be connected to the electrodes of the circuit board.

The first connector **10** may include any one of the set of signal terminals **13a** to **13k** and the set of signal terminals **13l** to **13v**.

What is claimed is:

1. A connector comprising:
a resin body member;
a plurality of signal terminals supported by the resin body member;
a ground terminal supported by the resin body member;
and
a floating terminal supported by the resin body member,
wherein
the resin body member includes

a protruding portion extending in a right and left direction when viewed in an up and down direction,
a frame portion having an annular shape surrounding the protruding portion when viewed in the up and down direction, and
a coupling portion between the protruding portion and the frame portion when viewed in the up and down direction, the coupling portion coupling the protruding portion to the frame portion,

11

the plurality of signal terminals is supported by the frame portion and arranged in the right and left direction in a region in front of or in back of the protruding portion, the floating terminal covers at least part of a left end of the protruding portion when viewed in the up and down direction and is not connected to any of terminals of the connector, including the plurality of signal terminals and the ground terminal,

the ground terminal is supported by the frame portion and opposed to the floating terminal in a front and rear direction or in the right and left direction, 10

the ground terminal includes a first part opposed to the floating terminal in the right and left direction,

the connector further comprises a through-hole extending 15 through the coupling portion in the up and down direction in at least part of a region between the first part and the floating terminal when viewed in the up and down direction,

the ground terminal includes a ground protrusion protruding into the through-hole when viewed in the up and down direction, 20

the floating terminal includes a floating protrusion protruding into the through-hole when viewed in the up and down direction, and 25

the ground protrusion and the floating protrusion are arranged in the right and left direction.

2. The connector according to claim 1, wherein

the floating terminal includes a first part opposed to the ground terminal in the right and left direction, and a floating protrusion extending in a leftward direction from a lower end of the first part, and

a width of the first part in the front and rear direction is greater than a width of the floating protrusion in the front and rear direction. 30

12

3. The connector according to claim 1, wherein the floating terminal includes a first part on a top surface and a left surface of the protruding portion, a second part extending in a forward direction from the first part and on the front surface of the protruding portion, and a third part extending in a rearward direction from the first part and on a rear surface of the protruding portion.

4. The connector according to claim 3, wherein the first part and the second part are not coupled on the left surface or the front surface of the protruding portion, and

the first part and the third part are not coupled on the left surface or the rear surface of the protruding portion.

5. The connector according to claim 3, wherein a width of the first part in the front and rear direction is greater than any of a width of the second part in the right and left direction and a width of the third part in the right and left direction.

6. The connector according to claim 2, wherein the floating terminal includes a first part on a top surface and a left surface of the protruding portion, a second part extending in a forward direction from the first part and on the front surface of the protruding portion, and a third part extending in a rearward direction from the first part and on a rear surface of the protruding portion.

7. The connector according to claim 6, wherein the first part and the second part are not coupled on the left surface or the front surface of the protruding portion, and

the first part and the third part are not coupled on the left surface or the rear surface of the protruding portion.

8. The connector according to claim 4, wherein a width of the first part in the front and rear direction is greater than any of a width of the second part in the right and left direction and a width of the third part in the right and left direction.
